CLAIM

The ornamental design for a tile for animal communications, as shown and described.

DESCRIPTION

FIG. 1 is a perspective view of a tile for animal communications according to the design.

FIG. 2 is a top view of the tile of FIG. 1.

FIG. 3 is a front elevation view of the tile of FIG. 1.

FIG. 4 is a left side elevation view of the tile of FIG. 1.

FIG. 5 is a right side elevation view of the tile of FIG. 1.

FIG. 6 is a rear elevation view of the tile of FIG. 1; and,

FIG. 7 is a bottom view of the tile of FIG. 1.

The broken lines illustrate portions of the tile for animal communications that form no part of the claimed design.

1 Claim, 7 Drawing Sheets
